UNITED STATES PATENT OFFICE.

EUGENE SEAVEY, OF NEW YORK, N. Y., ASSIGNOR TO C. V. PRODUCTS CORPORATION,
A CORPORATION OF NEW YORK.

SHANK STIFFENER.

Application filed July 30, 1923. Serial No. 654,680.

To all whom it may concern:

Be it known that I, EUGENE SEAVEY, a citizen of the United States, residing at New York, in the county of New York and State of New York, have invented new and useful Improvements in Shank Stiffeners, of which the following is a specification.

This invention relates to shank stiffeners and more particularly the invention relates to shank stiffeners of the type shown in my co-pending application Serial No. 596,827, filed Oct. 25, 1923.

The principal object of the invention is the provision of a shank stiffener for shoes wherein the attaching means is concealed between the welt strips thereby giving the same a neater appearance.

A further object of the invention is to provide a shank stiffener having a rubber tread surface adapted to be secured at the shank portion of a shoe to arrest the strain usually distributed between the ball of the foot and the heel.

Another object of the invention is the provision of a shank stiffener including attaching plates adapted to be secured between the welt strips of a shoe, and a shank supporting block secured to the plates and disposed exteriorly of the sole adjacent the heel of the shoe.

A still further object is to provide a shank stiffener having a non-skid yieldable tread surface which may easily be removed when worn and a new one substituted therefor.

A still further object is to provide a shank stiffener which is simple in construction, easy to apply or remove from a shoe, cheap of manufacture and highly efficient for the purpose intended.

With these and other objects in view, the invention resides in the certain novel construction, combination and arrangement of parts, the essential features of which are hereinafter fully described in the specification, are pointed out in the appended claims, and are illustrated in the accompanying drawing, in which:

Figure 1 is a side elevation of my device applied to a shoe.

Figure 2 is a bottom plan view of the same.

Figure 3 is a transverse sectional view

therethrough on the line 3—3 of Figure 1.

Figure 4 is a detail perspective view of the attaching plate.

Figure 5 is a detail perspective view of the supporting member.

Figure 6 is a view showing a slight modification.

Figure 7 is a detail perspective view of the attaching plate used in the modification.

In my co-pending application above referred to, I have secured the attaching plate to the exterior of the sole thereby exposing the same to view. I have now devised a way of concealing the attaching plate between the welt strips, this style of shank stiffener being attached to the shoe at the factory during the manufacture of the same. This is intended to give a neater appearance to the article.

Referring more particularly to the drawing, and especially to Figures 1 to 5 inclusive, the reference numeral 10 designates a shoe of the usual well-known construction which includes a sole 11, welt strips 12, and heel 13. My improved shank stiffener 14 has its anchorage between the welt strips 12 at the shank portion of the shoe, and a portion of the same abuts the heel 13 as will now be described.

A shank stiffener 14 includes a pair of plates 15 adapted to be interposed between the welt strips 12 and arranged in parallel relation to each other. Each plate 15 is provided with a plurality of openings 16 for the reception of suitable fastening elements 17 for engagement with the welt strips 12. The plates 15 are formed with a struck-out portion in the nature of a longitudinal track 18. When the plates are in their respective positions upon a shoe the tracks 18 are in converging relation to each other in cross-section for a purpose to be described. The front ends of the tracks are bevelled as at 19 so as not to scrape the ground when the rubber support member 20 has worn down to the tracks. The tracks 18 extend through slits 21 in the sole 11 for removably receiving the support member 20. The member 20 is formed of a yieldable material such as rubber and has its front wall rounded as at 22 so as not to present short corners which might prove uncomfortable to the wearer while walking. The member

20 is formed with a pair of spaced grooves 23 opening into the top of the member and arranged in converging relation to each other so as to permit the member to be slid 5 along the tracks 18 to a position against the heel 13 as clearly shown in Figure 1 of the drawings. The tread surface of the support member is formed centrally with a vacuum cup 24 and a plug of non-slip abrasive material 25 so that a positive ground gripping surface is provided. It will be seen that after the member 20 has been slid to its position upon the attaching plate, the tracks and grooves form a dovetail lock. When 10 the tread surface has worn, the member 20 may be slid off the tracks and a new one substituted therefor, or if desired the member might be removed and left off and the tracks bent down against the sole as the plates 15 15 are capable of stiffening the shank to a certain degree. It will also be seen that the usual metal plate inserted at the shank of the shoe between the welt strips is dispensed with when my stiffener is used.

20 In the form of my invention shown in Figures 6 and 7 the construction is identical to that of the preferred form, with the exception that instead of using two plates, I employ a single attaching plate 15' having 25 upstruck tracks 18'. This form of plate is secured to the outside of the sole as clearly shown in Figure 6.

While there has been shown and described what I deem to be the best embodiment of my invention, I wish it to be understood that I do not limit myself to the precise structural detail herein exhibited and to nothing less than the whole of my invention limited only by the appended claims, and 30 that changes, alterations and modifications as come within the claims may be resorted to when desired.

What is claimed as new is:

1. In a device of the class described, the 45 combination of a shoe having welt strips; a sole and a heel, a pair of plates having their body portions concealed between the welt strips, rails formed on said plates and extending exteriorly of the sole, and a supporting member carried by said rails and arranged flush with the front of the heel and

extending slightly beyond the arch portion of the sole.

2. In a device of the class described, the combination of a shoe having welt strips, a sole and a heel, a pair of plates having their body portions concealed between the welt strips, rails formed on said plates and extending exteriorly of the sole, and a supporting member slideable on said rails and arranged flush with the front of the heel and extending slightly beyond the arch portion of the sole.

3. In a device of the class described, the combination of a pair of plates adapted to be secured and concealed between the welt strips of a shoe, a supporting member, and means for securing said supporting member to said plates exteriorly of the sole.

4. In a device of the class described, the combination of a pair of plates adapted to be secured and concealed between the welt strips of a shoe, a yieldable non-skid supporting member, and means for removably securing said supporting member to said plates exteriorly of the sole of the shoe.

5. In a device of the class described, the combination of a pair of plates adapted to be secured between the welt strips of a shoe, a yieldable non-skid supporting member, with grooves formed therein, and means for removably securing said yieldable supporting member to said plates exteriorly of the sole, said means including a pair of longitudinal tracks for co-action with the grooves formed in said supporting member.

6. A shank stiffener comprising a pair of tracks, means for attaching said tracks to the arch portion of a shoe, and a tread member having grooves for co-action with said tracks for sliding movement thereon.

7. A shank stiffener comprising a pair of parallel tracks arranged in converging relation to each other in cross-section, means for attaching said tracks to the arch portion of a shoe, and a rubber tread member having its underside provided with grooves for co-action with said tracks for detachable connection therewith.

In testimony whereof I have affixed my signature.

EUGENE SEAVEY
